US0D1082780S

(12) **United States Design Patent** (10) **Patent No.:** **US D1,082,780 S**
(45) **Date of Patent:** **** Jul. 8, 2025**

(54) **ERGONOMIC KEYBOARD**

(71) Applicant: **Logitech Europe S.A.**, Lausanne (CH)

(72) Inventors: **Axelle Justafré**, Lausanne (CH);
Ching-Fei Cheng, New Taipei (TW);
Nicolas Jinkinson, St-Sulpice (CH);
Tanyel Yalazoglu, Geneva (CH)

(73) Assignee: **Logitech Europe S.A.**, Lausanne (CH)

(**) Term: **15 Years**

(21) Appl. No.: **29/978,456**

(22) Filed: **Dec. 12, 2024**

Related U.S. Application Data

(63) Continuation of application No. 29/874,920, filed on Apr. 26, 2023, now Pat. No. Des. 1,060,339.

(57) **CLAIM**

The ornamental design for an ergonomic keyboard as shown and described.

DESCRIPTION

FIG. 1 is a perspective view of an ergonomic keyboard showing our new design;

FIG. 2 is a rear perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left-side elevation view thereof; and,

FIG. 8 is a right-side elevation view thereof.

The broken lines shown in the figures illustrate portions of the ergonomic keyboard that form no part of the claimed design.

1 Claim, 5 Drawing Sheets
